UNITED STATES PATENT OFFICE.

REISSUED

STEPHEN S. NEWTON, OF BINGHAMTON, NEW YORK.

DESIGN FOR A PACKAGE FOR POWDERED ARTICLES.

SPECIFICATION forming part of Design No. 11,965, dated September 14, 1880.

Application filed July 1, 1880. Term of patent 7 years.

To all whom it may concern:

Be it known that I, STEPHEN S. NEWTON, of Binghamton, county of Broome, State of New York, have invented a new Design for 5 Package for Bluing or other Articles of Commerce, of which the following is a full and complete description, reference being had to the accompanying drawing, and to the letters of reference marked thereon.

10 In the drawing, which is an elevation of my new design, A represents the base of the vessel; B, the lower part of the body; E, the cap or cover, and D the upper part of the body between the cover and the part B.

15 The base A is of the form of a frustum of a cone, the outer surface being somewhat concave, but circular at all points in cross-section. Immediately above the base A there is a laterally-projecting fillet or bead, C.

20 The body B D extends from the bead or fillet C to the cap E, the lower part, B, being of the form of a frustum of a cone in an inverted position, with its outer surface circular in cross-section at all points. At its upper end the 25 part B is substantially of the same diameter as the cap E.

The upper part, D, of the body is of the form of a ring whose outer surface is curvilinear in vertical section, and of the same contour 30 throughout, and having the diameter of the upper side equal to that of the lower.

In order to make a stronger and more pleasing contrast between the cap B and the ring

part D, I form in the outer surface of the vessel a recess, d, between these parts.

The base is hollow or concave on the under side, and is formed with a series of radial flutings, a.

I am aware that vessels have been constructed with bodies in the form of truncated 40 pyramids polygonal in cross-section, and that others have been formed with bodies in the form of inverted truncated cones having the diameter of their upper ends much larger than that of the necks or caps of the vessels, and 45 I do not claim such forms or designs.

What I claim is—

The design herein described and shown for packages for powdered articles, having the base A of the form of a truncated cone, the 50 lower part, B, of the body of the form of an inverted truncated cone, the laterally-projecting fillet C at the junction of the parts A and B, the upper part, D, in the form of a ring curvilinear in outline in cross-section, which extends 55 from the part B to the cap and is of equal diameter at the top and bottom, and the recess d at the junction of the parts B and D.

In testimony that I claim the above I have hereunto set my hand this 28th day of June, 60 1880.

STEPHEN S. NEWTON.

In presence of—

JOHN B. HAGAMAN,
S. E. LAMOUREUX.
